Specification for Design.

Patented Nov. 11, 1919.

Application filed August 25, 1919. Serial No. 319,834. Term of patent 14 years.

To all whom it may concern:

Be it known that I, CLARK A. SWINEHART, a citizen of the United States, residing at Springfield, in the county of Clark and State of Ohio, have invented a new, original, and ornamental Design for Pneumatic-Tire Treads, of which the following is a specification, reference being had to the accompanying drawing, forming part thereof.

The figure is a plan view of a portion of a pneumatic tire casing showing my new design.

I claim:

The ornamental design for a pneumatic tire tread, as shown.

CLARK A. SWINEHART.
